(57) **CLAIM**

The ornamental design for a heating plate for crepe maker as shown and described.

DESCRIPTION

FIG. 1 is a side, perspective view showing my new design for a heating plate for crepe maker shown in use with an exemplary crepe maker base.

FIG. 2 is a side, perspective view thereof, shown with the crepe maker base removed, to show aspects of the design not visible when combined.

FIG. 3 is front elevation view thereof.

FIG. 4 is a rear elevation view thereof.

FIG. 5 is a side elevation view thereof.

FIG. 6 is a side elevation view thereof from the side opposite FIG. 5.

FIG. 7 is a top plan view thereof; and,

FIG. 8 is a bottom plan view thereof.

The evenly broken lines represent both parts of the article as well as environmental subject matter of an exemplary crepe maker base. None of the broken lines form part of the claimed design.
